Dogwood Patent and Trademark Law(57) **CLAIM**

The ornamental design for a cornhole board, as shown and described.

DESCRIPTION

FIG. 1 is a top front right perspective of a cornhole board showing our new design;

FIG. 2 is a bottom front left perspective view thereof;

FIG. 3 is a top rear left perspective view thereof;

FIG. 4 is a front elevational view thereof;

FIG. 5 is a rear elevational view thereof;

FIG. 6 is a right elevational side view thereof;

FIG. 7 is a left elevational side view thereof;

FIG. 8 is a top plan view thereof; and,

FIG. 9 is a bottom plan view thereof.

The broken lines in the drawings depict portions of the cornhole board that form no part of the claimed design. The drawings are shown with a symbolic break in the length of the leg's screws. The appearance of any portion of the article between the break lines forms no part of the claimed design.
